UNITED STATES PATENT OFFICE.

GUSTAV H. MOLL, OF ST. LOUIS, MISSOURI.

UMBRELLA.

SPECIFICATION forming part of Letters Patent No. 284,043, dated August 28, 1832.

Application filed March 15, 1833. (No model.)

To all whom it may concern:

Be it known that I, GUSTAV H. MOLL, of the city of St. Louis, State of Missouri, have invented a new and useful Improvement in 5 Umbrellas, of which the following is a full, clear, and exact description.

The object of my invention is to provide certain new and useful improvements in umbrellas, whereby the same can be locked so 10 that they cannot be opened except by the owner or possessor of a fitting handle.

Reference is to be had to the accompanying drawings, forming part of this specification, in which similar letters of reference indicate corresponding parts in all the figures.

Figure 1 is a longitudinal sectional elevation of the upper part of an umbrella provided with my improvements, the handle being held on the stick. Fig. 2 is a like view, 20 showing the handle removed. Fig. 3 is a perspective view of the latch-plate. Fig. 4 is a longitudinal sectional elevation of the upper part of an umbrella, showing a modified construction of my improved locking device.

25 The umbrella-stick A is provided in its lower end with a longitudinal aperture, A', adapted to receive the spindle B at the upper end of the removable handle C. The stick is provided with a longitudinal slot, D, 30 over which a strip, E, is secured on the outer surface of the stick, which strip is provided with jaws F, projecting into the slot, in which jaws a lever, G, is pivoted, which is provided at its upper end with a bend, hook, head, or 35 prong, H, which projects outward, and is adapted to pass through that end of the slot D which is nearest the end of the stick and is not covered by the strip E. A spring, J, secured to the inner surface of the strip E 40 and within the slot D, presses the lower part of the lever G inward. The cup K, for confining the ends of the ribs together, is held to slide on a ferrule, L, on the lower end of the stick A, and is provided with an annular groove, M, or with an aperture, notch, or 45 recess for receiving the upper end of the lever G. Any suitable device may be used for locking the handle on the lower end of the stick.

50 In the modification shown in Fig. 4 the umbrella is not provided with a cup, K; but

the runner T is provided with an aperture, U, into which the upper end of the latch H snaps when the handle is withdrawn, thereby locking the ribs when the umbrella is closed, if operating the same as described above in relation to the cup.

55 The device operates as follows: If the cup K is pressed down over the ends of the ribs N, and the handle C is removed, and the spindle B withdrawn, the spring J presses the lower end of the lever G inward and the upper end of the said lever outward, so that it enters the groove M and holds the cup K in place, preventing removal of the same. 60 The umbrella is then of no use whatever to any person not in possession of the handle, as it cannot be held and cannot be opened, as the ribs are held together by the locked cup K. As soon as the handle-spindle B is 65 pushed back into the aperture A', the lower end of the lever G is pressed outward, the upper end inward and out of the groove M, and thereby the cup K is released and can be raised to release the ends of the ribs N. The 70 handles can be so constructed that they will only fit the proper umbrella, and no other handle will fit the aperture in the stick of the 75 said umbrella.

I am aware that it is not new to combine 80 a staff with a spring having double catches, a runner with double slots and a cap, or to combine an inner tube with a removable handle; but

85 What I do claim as new and of my invention is—

1. The combination, with the lever G, supported on a spring, D, at one end, of the umbrella-stick A, having a perforation extending beyond said lever, and the spindle B, movable in said perforation, whereby the lever may be vibrated against the resistance of the spring, as described.

2. The combination, with the lever G, supported at one end on a spring, J, and provided at the other with a bent end, H, of the stick A, having slot D, the strip E, having jaws F, and the cup K, having the groove M, as and for the purpose specified.

90 95 100 3. The combination, with an umbrella-stick, A, having an aperture, A', and slot D, of the ferrule L, the cup K, having an annular groove,

notch, or recess, the locking-cover G, and the removable handle C, substantially as herein shown and described, and for the purpose set forth.

5 4. The combination, with the umbrella-stick A, having an aperture, A', and a slot, D, of the ferrule L, the cup K, the strip E, having jaws F, the lever G, the spring J, and the re-

movable handle C, substantially as herein shown and described, and for the purpose set forth.

GUSTAV H. MOLL.
